(57) **CLAIM**

The ornamental design for a camping tent, as shown and described.

DESCRIPTION

FIG. 1 is a first perspective view of a camping tent showing the claimed new design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plane view thereof;

FIG. 8 is a bottom plane view thereof; and,

FIG. 9 is a perspective view thereof with the front flap in an open position.

The broken lines are for the purpose of illustrating portions of the article that form no part of the claimed design.
